(57) **CLAIM**

The ornamental design for an electrical equipment housing cover, as shown and described.

DESCRIPTION

FIG. 1 is a perspective view of an electrical equipment housing cover with the top (shorter width) surface of the cover facing the viewer.

FIG. 2 is the opposite perspective view of the electrical equipment housing cover.

FIG. 3 is a front elevation view of the electrical equipment housing cover.

FIG. 4 is a bottom view of the electrical equipment housing cover; and,

FIG. 5 is a top view of the electrical equipment housing cover.

The rear view of the electrical equipment housing cover forms no part of the claimed design.

The broken line environmental showing is for illustrative purposes only and forms no part of the claimed design.
